UNITED STATES PATENT OFFICE

PETER SWANSON, OF ELY, MINNESOTA

SWITCH STAND LOCK

Application filed October 23, 1930. Serial No. 490,670.

This invention relates to railway switch stand locks and in some respects is an improvement upon my former invention covered by Patent No. 1,773,326 dated August 19th, 1930; however, differing in respect to the form of switch stand to which the present invention is particularly adapted in that the head of the instant switch stand is only rotatable in respect to opening or closing the switch, whereas my said former invention was applied to a stand in which the head is both rotatably and reciprocably movable when the switch is operated.

The principal object is obviously that of producing a more practical, simple, and dependable locking mechanism than heretofore known, and other more specific advantages of the novel structure will appear in the following description of the invention.

Referring now to the accompanying drawings, wherein like reference characters indicate like parts.

Figure 1 is a top plan view of a common switch stand head, with my improved lock applied thereto;

Figure 2 is an enlarged side elevation of same showing the housing of the lock in section;

Figure 3 is a somewhat reduced external perspective view of the lock as assembled; and

Figure 4 is an enlarged perspective view of the operating portions of the lock mechanism.

1 represents the head of the now common railroad switch stand as used upon main line tracks, and through which the square signal staff 2 extends axially, and carrying the operating lever 3 upon one side thereof, said lever being pivotally mounted as at 4 within the slotted laterally extending portion 5 of the head 1, it being well known to those versed in the art that this lever 3 must be raised to substantially horizontal position before the head 1 can be turned to throw the switch.

The locking mechanism is mounted within a two-part separable housing designed to be fixed upon the extension 5 as for example by the two bolts indicated at 6, the housing comprising the inner compartment indicated at

7, of which the projecting base portion 8 forms an integral part, while the other or hood portion of the compartment is indicated at 9. The lock is only possible of complete assembly after the two portions of the housing are cooperatively united, they being held together by the final placing of the locking shaft in position therewithin.

The locking shaft is composed of a unitary member, normally horizontally disposed within the housing, and having one extreme end as at 10 journalled within the assembly walls of the housing, and the opposite enlarged inner extremity 11 also journalled within the walls of the housing. That portion of this locking shaft intermediate of the two bearings just described is somewhat novel in shape for conveniences hereinafter described, but it is generally rectangular in form throughout except as to the offset portion indicated at 12 which provides a crank arm carrying a spindle 13 thereupon for the eccentric pivotal support of the locking dog 14 on the crank arm.

The locking dog 14 is of L-shape and depends from the spindle 13 through the hole 15 in the base 8 of the lock housing, and also through a similar hole or opening 16 through the upper face of the extension 5 of the switch stand head 1, and with which the opening 15 in the base 8 registers when the housing is in place upon the switch head. The horizontal portion or head 17 of the dog when in its lowermost position registers intermediate of the upper free end of the lever 3 and the rearmost wall of the opening or slot in which the lever 3 is pivotally mounted and thereby prevents the lever from being raised on its pivotal support 4 for the turning of the switch. However, when the dog 14 is raised by the rotation of the locking shaft it is free from acting as an obstruction to the free end of the lever 3 so that the same may be readily thrown to open position for operating the switch by rotating the head 1. This rotation of the locking shaft is accomplished by throwing the balled crank arm 18 in clockwise direction as viewed from the side opposite to that of the staff. The crank arm 12 performs a double function in that when in

its lowermost position it prevents outward motion of the locking shaft by engaging the fixed pin 19 integral with the base 8 of the housing, and the ball 20 on the crank arm 18 provides the necessary gravity bias to hold the locking dog 14 in its elevated position unless otherwise adjusted.

A novel feature of the peculiar construction of the locking dog is that its throat is 10 cut away as at 21 somewhat abnormally, and the back of the head as at 22 is similarly shaped so that before the housing is applied to the extension 5 of the switch stand head the dog may be placed through the hole 16 15 into the cut out or slotted portion of the extension and there held in any desired manner from beneath the extension while the housing for the lock and the locking mechanism are applied, thus avoiding the necessity 20 of removal of the switch lever 3, this being a decided advantage in the quick and economical installation of the lock upon such switch stand heads.

Now the mechanism for control of the rotatable or rockable locking shaft within the lock housing is similar in many respects to my former patent above cited; however, novel in others and deemed worthy of protection in this application, to wit: the innermost portion of the housing forming the chamber 7 has extending centrally and upwardly therefrom two spaced rectangularly shaped wall members 23, intermediate of which the locking dog 24 is pivotally mounted as at 25 and functions both in cooperation with the locking shaft and the key for the lock. That portion of the dog 24 to one side or forwardly of the pivotal connection 25 is generally L-shaped, having the depending 40 head 26 formed integral therewith and which head at the time the mechanism is left in locked position extends downwardly as shown in dotted lines intermediate of the squared portion 27 of the locking shaft and 45 the adjacent inner wall of the housing, the dog being shown in such position in both Figures 2 and 4. This dog is also provided with a tail 28 with suitable means for securely retaining the expansive helical spring 50 29 between it and the upper wall of the inner portion of the housing so that the dog is normally held by the action of said spring in the position just described, and the limit of this engagement is determined both by the 55 contact of the upper side of the tail 28 with the inner roof wall of the outer portion of the housing and also by the stepped shoulder 31 formed on the side of the dog. Centrally and beneath the pivotal connection 25 of the 60 dog is integrally formed the arcuately shaped closure member 32 for the key-hole, it being so designed as to free the key for entrance or withdrawal at any time the device is in locked position, but absolutely prevents withdrawal of the key when in any other position.

It will be further noted that when the key is inserted as shown in the drawings and turned clockwise as viewed from the side through which the key is applied, it will raise the dog 24 and in the raised position the dog may be held by the key unattended if the latter is turned a full half turn so as to permit of the entire operation of unlocking and turning the switch being accomplished with one hand, for as the dog 24 is thus left in elevated position with the key in place, the same hand may be employed in throwing the crank arm 18 down to horizontal position which lifts the locking dog 14, and the gravitating effect of the ball 20 on the lever 18 will retain the locking dog in elevated position and in said position of the dog 24 the lever 3 may be raised and the switch thrown. Or the dog 24 may be raised by the key in one hand until the locking shaft is rotatable when the dog may be allowed to snap back onto the shaft and there remain until the latter is reversely rotated to locked position, thereupon the dog 24 will snap back by the action of the spring 29 to its locked relation with the shaft, after which the key may be removed, but at no time can the key be removed unless the switch is left in locked position.

It will be noted that when the gravity lever 18 is thrown so that the locking shaft is in unlocked position, the upward throw of the dog 14 will be limited by its pivotal end engaging the under side of the top of the innermost portion of the housing, and that when the locking shaft is rotated to its extreme opposite position the side of the squared portion of the shaft will engage a slightly protruding portion as indicated in dotted lines at 33, so that the action of the shaft is positively stopped in either direction.

Another novel feature of my present structure is that I have recessed the base 8 of the inner portion of the housing so that it overlaps the extension 5 upon the three exposed sides thereof in making a neat looking and strong assembly, and while I have shown the base 8 as applied to the extension 5 as by the two tap screws or bolts 6, it will be noted that housing projections 30 are formed integral with the external portion 9 of the housing, so that when the latter is in place, access to these bolts as by a wrench or the like is impossible, thus further insuring against tampering.

The key for the lock is designated by the numeral 34, and may be of the conventional type, and to facilitate operation of the device by those unaccustomed to same, the words "Lock" and "Open" appear on the top of the housing, with appropriate arrows adjacent same, indicating the position to which the balled crank arm is to be manually operated to accomplish such functioning of the lock.

It will of course be understood that various means may be resorted to in attaching the lock to the switch stand, particularly when it is

attached to a stand of a type other than herein described, and that various other modifications may be resorted to without departing from the spirit of the invention as defined in the following claims.

Having thus described my invention, what I claim and desire to secure by Letters Patent, is:

1. A switch stand lock comprising a housing having a key hole therein, a rotatable shaft mounted within said housing, a locking dog eccentrically mounted on said shaft, and a gravity and spring actuated pawl for normally holding said shaft against rotation.

15 2. A switch stand lock comprising a housing, a rotatable shaft mounted within said housing, a vertically movable locking dog eccentrically mounted on said shaft, and a pawl for normally holding said shaft against rotation.

20 3. A switch stand lock of the type described having a vertically reciprocable locking dog and a rockable shaft for operating said dog, of a key controlled dog for locking or unlocking the shaft, means whereby said latter dog may or may not be left in inactive position in respect to the shaft, and means whereby the key can not be removed from the lock unless the locking dog is in its ultimate locked

25 30 position.

4. A switch stand lock comprising a vertically reciprocable locking dog, a rockable shaft for operating said dog, a key controlled dog for locking or unlocking the shaft, and means whereby said latter dog may or may not be left in inactive position in respect to the shaft.

35 5. A switch stand lock comprising a vertically reciprocable eccentrically mounted dog, a rockable shaft for operating said dog, a key controlled dog for locking or unlocking the shaft, and means whereby said latter dog may or may not be left in inactive position in respect to the shaft.

40 45 6. The combination with a switch stand head of the type described having a laterally extending slotted portion for the reception of a pivotally mounted operating handle, and a hole through the roof of the slotted portion, of a lock having a vertically reciprocable dog therein for cooperation with the operating handle within the slot, said dog being so shaped as to readily enter said hole and permit of the lock being applied to the stand

50 55 without removing the handle.

7. The combination with a rotatable switch stand head having an operating handle and an extension thereupon for pivotally carrying the operating handle, of a two-part telescopic lock housing mountable upon the extension and overlapping same upon three sides thereof.

8. In combination a switch stand head, a telescopic lock containing housing mountable 60 65 upon the head, bolts for securely fixing the in-

nermost portion of the housing to the head, and means whereby the outermost portion of the housing renders said bolts inaccessible when the housing is assembled.

9. In combination a switch stand head having an extension provided with a slot therein, an operating handle pivoted within said slot, and a reciprocal locking dog within the slot cooperatively engageable with the handle in either of its extreme positions.

70 10. In combination, a switch stand head having an extension provided with a slot therein, an operating handle pivoted within said extension, and a vertically reciprocal locking dog within the slot cooperatively engageable with the handle in either of its extreme positions.

75 In testimony whereof I affix my signature.

PETER SWANSON.
